UNITED STATES PATENT OFFICE.

FRANK H. TREACY, OF POUGHKEEPSIE, ASSIGNOR TO JAMES H. SWIFT, OF AMENIA, AND EDWIN THORNE, OF MILLBROOK, NEW YORK.

SWITCH AND SIGNAL MECHANISM.

SPECIFICATION forming part of Letters Patent No. 369,823, dated September 13, 1887.

Application filed March 1, 1887. Serial No. 229,316. (No model.)

To all whom it may concern:

Be it known that I, FRANK H. TREACY, of Poughkeepsie, in the county of Dutchess and State of New York, have invented certain new and useful Improvements in Switch and Signal Mechanism; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to combined mechanism for operating switches, locking devices, and signals either simultaneously or consecutively; and its object is to simplify the construction, increase the accuracy and certainty of operation, and consequently lessen the danger of accidents.

My invention consists of the combination, in a suitable mechanism, of means for shifting the switch, of a compensating device allowing an excess of movement in certain parts, a locking mechanism, a detector-bar, and a pair of signaling devices connected with said parts, and an intermediate mechanism between said signaling devices and the operating parts aforesaid, whereby the signals will be moved only either before or after the switch has been shifted.

My invention also consists in the combination, with the operating parts of a switch mechanism, of the movable rails, and a pair of semaphore-blades, with a compensating locking device between said operating parts and rails and another compensating device between said operating parts and said blades, the whole combined and arranged in such a manner that when the rails are being moved the blades will remain at rest in a position to indicate "danger," and will not move to "safety" until after the rails have been moved and locked.

My invention also consists in certain other combinations and arrangements of parts, as hereinafter described, and particularly pointed out in the claims.

Referring to the accompanying drawings, Figure 1 is a plan view of a section of track, showing a switch provided with my improved

shifting, locking, and signaling devices, all the parts being in the position they would occupy when the shifting of the switch has been half accomplished. Fig. 2 is a side elevation showing the detector-bar. Fig. 2^a is a detached view, and Fig. 2^b is a detached detail, of my invention. Figs. 3, 4, 5, 6, 7, 8, 9, 10, 11, 12, and 13 illustrate the signaling devices.

Similar letters refer to corresponding parts in all the views.

The track is composed of rails A of the ordinary construction. The movable rails B constitute the well-known "split" switch. One or more of the ties C are preferably larger than the rest to afford convenient support for certain parts of the switch mechanism constituting what may be called a "compensating locking movement," which will now be described.

The rod a leads from a signal-tower or other point (not shown) to the lever a², which is fulcrumed to a base-plate fastened to a tie C. At its outer end the lever is provided with a lug, a⁴, which may, if desired, be provided with one or more anti-friction rollers, while the other end of the lever may extend beyond the fulcrum, as shown. Pivoted to the base-plate at a point a little in front of the fulcrum of lever a² is a double-faced and centrally-notched cam, a'. The construction of this cam and its operation in connection with lever a² have been fully set forth and specifically claimed in my application filed December 10, 1886, Serial No. 221,218, and need not be here described in detail. Briefly stated, it may be said that when the lever a² is moved the lug a⁴ engages with the notch a⁵ in the center of the cam a', and turns the cam upon its pivot; but, as the lever is pivoted eccentrically to the cam, the radius of the arc described by the lug a⁴ is greater than that described by the notch in the cam. The lug therefore soon leaves the notch and glides along one of the curved faces of the cam, which extend each way from the notch. The curvature of these faces corresponds with the arc described by the lug a⁴, so that the movement of the lug after it leaves the notch does not turn the cam any farther; but it does prevent the cam from turning back again. The cam will thus be turned a prede-

terminated distance and no more, irrespective of the excess of travel of the lug a^4 , and thus constitute a compensating locking movement which has a fixed range of oscillation from one 5 predetermined point to another. Moreover, the actuation of the cam is accomplished in a comparatively-short interval, and while the lug a^4 is traversing a short portion of its arc.

To the cam a' is pivoted one end of a short 10 link connecting it with the switch-bar a' . The extent of oscillation of the cam is of course so arranged as to be just sufficient to shift the switch-bar a' and the movable rails B from one position of the switch to the other.

15 It will be seen that when one of the rails B has been brought against the adjacent rail, A, the switch will be locked by the movement a a^2 a^4 , since the lug a^4 prevents any backward turning of the cam; but in order to relieve 20 these parts of strain and shock I provide a separate locking mechanism, which is operated by the same motion of the rod as that which actuates the switch.

The points of the movable rails B are connected 25 by a flat bar, F', which is provided with two perforations, f f, and slides through a guide, D, fastened to one of the ties. In a tubular portion of the guide D is a sliding bolt, F, arranged at right angles to the bar F'.

30 This bolt F is reciprocated by means of rod d^2 , bell-crank lever d' , and rod d . It is obvious that it must not be thrown forward again until the rails B have come to rest, and that this must be accomplished when the switch is shifted in 35 either direction. In order to effect this result, I locate a lever, b' , so as to be in line with the rod d when the bolt F is withdrawn, as shown in Fig. 1. It will be seen that any movement of the lever either way from this central position will exert a pull on the rod d and throw the bolt F forward into engagement with one 40 of the perforations in the bar F'. In order to move the lever b' , I connect it with the lever a^2 by means of a rod, b. The motion of lever a^2 before its lug a^4 engages the cam a' will bring the lever b' up toward its central position and withdraw the bolt F, leaving the rails free to be shifted by the cam. While this is 45 being effected the lever b' will reach and pass its central position, and the further excess of travel of the lever a^2 will carry the lever b' far enough beyond said position to throw the bolt forward into its perforation f in the bar F', which has already come to rest, when the motion 50 of the cam a' ceased. The same operation will ensue when the switch is shifted to the opposite side. In connection with all these parts I employ a detector-bar. This detector-bar E' is arranged alongside one of the rails A,

55 and is pivoted to the upper ends of the several short parallel links e, the lower ends of which are pivoted to lugs or ears on the flange of the rail A. The upper edge of the bar E' lies normally just below the top of the rail. A rod, E, connects the detector-bar with the lever a^2 , preferably with the extended rear end of said lever, as shown in Fig. 1. When

the lever is thrown from one side to the other, the detector-bar E' will be raised, carried lengthwise, and then lowered again, since the 70 upper ends of links e describe arcs of small circles. When the detector-bar is down and a train passes over the switch, the wheels of the train prevent the detector-bar from rising, and consequently prevent the switch from being shifted, either accidentally or intentionally, 75 until the train has passed.

In order that the engineer of an approaching train may be apprised of the condition of the switch, I erect at any suitable spot a signal post, G, provided with two signaling devices, H I, one for the main track and one for the siding. These may be semaphore-blades, as shown, or numbered disks, or any suitable devices for attracting attention. Upon a stud, 80 g, projecting from the post G, are journaled two arms, L M, and a lever, K, the latter being between the two arms, as shown in Fig. 13. The end of the arm L is connected by a rod, H', with the signaling device H, and the arm 85 M is similarly connected with the other signaling device, I, by a rod, I', the arrangement being such that when the arm is raised the signaling device will be brought to "safety," but if the arm is allowed to fall the signal will indicate 90 "danger."

The lever K is provided with two laterally-projecting lugs, k k'. When the lever is swung to the right, as shown in Figs. 3 and 6, the lug k comes in contact with the arm L and raises it, bringing the signal H to "safety" and leaving the other at "danger." When the lever is moved to the left, as in Figs. 5 and 8, the signal I is brought to "safety" and signal H remains at "danger." When the lever hangs vertically, as in Figs. 4 and 7, both signals stand at "danger." In this position the space between the arms L and M is such that the lever K must swing through a certain arc before either of the lugs K K' will 100 strike its respective arm, so that by changing the signals from the position shown in Fig. 3 to that shown in Fig. 5 they will for a short time both stand at "danger," as shown in Fig. 4.

In order to swing the lever K, it is connected 115 by means of rod c, bell-crank lever c, and rod b², or other equivalent means, with lever b' or a^2 , as may be most convenient. The parts are so arranged and proportioned that when lever a^2 begins to move and the bolt F begins to be 120 withdrawn the lever K commences to lower the arm which it has been holding up, and the corresponding signaling device starts toward a position to indicate "danger." By the time the lug a^4 in the lever a^2 engages with the cam a' to shift the switch the bolt F has been withdrawn from perforation f in bar F', and the signaling devices are both standing at "danger," as in Fig. 4. While the cam a' is shifting the switch the lever K is swinging across 125 toward the other arm, both signals remaining at "danger," and when the switch closes and the lug a^4 leaves the notch the lever K strikes this other arm and brings down to "safety" 130

the other signal corresponding to the track which is clear. It will be seen that both signals remain at "danger" until the switch-rails have been unlocked and moved and locked again by the lever and cam. The arms K L M also act in the capacity of a compensating device, in that they allow an excess of movement of the rod c' without any material change in the relative position of the semaphore-blades.

It should be remarked that the detector-bar is raised nearly to its highest point before the cam a' is acted upon, and that in the descent its weight assists in moving the various parts of the mechanism.

It is obvious that the several parts of this switch and signal mechanism—viz., the switch-operating movement, the locking mechanism, the detector-bar, and the signaling devices—may be used separately, or in combination with other similar apparatus for accomplishing their object. Furthermore, the precise arrangement of lever and connection shown in the drawings may be more or less varied without departing from the spirit of my invention.

Having thus described my invention, what I claim, and desire to secure by Letters Patent, is—

1. The combination, with the rails B, of a pivoted double-faced cam, a' , located adjacent to the switch, the lever a^2 , having the lug a^4 to engage with a notch in said cam to turn it in either direction from a central position, and to lock the said cam when so turned, the said cam being pivoted between the pivot of said lever and its lug, a rod, a , connected with said lever to move the same, and a switch-bar, a^3 , pivoted to the cam and connected with the rails B, whereby the rails will be moved when the cam is turned, substantially as described.

2. In a switch mechanism, the combination, with the switch-bar, of the double-faced pivoted cam a' , the lever a^2 , having at one end a lug, a^4 , to engage with said cam, the other end of said lever being connected by rod E with the detector-bar E', whereby the detector-bar will be lifted nearly to its highest point before the cam is actuated to move the switch.

3. The combination, with the switch having the perforated locking-bar F', of the compensating locking-movement $a a' a^2 a^4$, the rod b , lever b' , and a bolt, F, actuated to engage with the locking-bar by a movement of lever b' in either direction from a central position.

4. The combination, with a switch having a perforated locking-bar, F', of the compensating locking-movement $a a' a^2 a^4$, the rod b , the lever b' , the rod d , connected with said lever b' , so as to lie substantially in line therewith when the lever is in its central position, the bell-crank lever d' , rod d^2 , and bolt F, whereby the bolt will be thrown forward by a movement of lever b' either way from a central position.

5. The combination, with a switch having a perforated locking-bar, F', of a bolt, F, rod d^2 , bell-crank lever d' , rod d , and lever b' , said

rod and lever lying substantially in the same line when the lever is in its central position, mechanism for operating the switch, and connection between said mechanism and the lever b' , whereby said lever will be moved from a point at one side of its central position to a point on the other side whenever the switch is operated, whereby the bolt F will be first withdrawn and then thrown forward again as the switch is operated.

6. The combination, in a switch mechanism, of the compensating locking-movement $a a' a^2 a^4$, the locking mechanism b , b' , d , d' , d^2 , F, and F', and the detector-bar E', and rod E, the rod b^2 , a two-bladed semaphore, and intermediate mechanism actuated by said rod and only operative to change the position of the blades before and after the switch is shifted.

7. In a switch mechanism, the combination, with the rod a , cam a' , and lever a^2 , of a locking mechanism and detector-bar operated simultaneously with said lever a^2 , a signal-post, G, carrying two semaphore-blades, H I, a lever, K, having the projecting lugs $k k'$, the arms L M, pivoted concentrically with lever K, rods H' I', connecting the blades H I with the arms L M, and connection between the lever K and the lever a^2 .

8. The combination, with a switch, of the rod a , cam a' , and lever a^2 , a signal-post, a lever, K, pivoted thereto and provided with lugs $k k'$, suitable connection between lever K and the lever a^2 , two arms, L M, pivoted concentrically with lever K, signaling devices H I, rods H' I', so that when the lever a^2 is first moved both signaling devices will come to "danger" and remain there until the lever a^2 has shifted the switch, when the further movement of the lever will throw down one of the signaling devices.

9. In a switch mechanism, the combination, with means for shifting the switch, of a single actuating-rod, a , connected with a compensating device allowing an excess of movement in certain parts, a locking mechanism, a detector-bar, and a pair of semaphore-blades connected with said parts, and an intermediate mechanism between said semaphore-blades and the operating parts aforesaid, whereby the blades will be moved only either before or after the switch has been shifted, the parts being so arranged and connected that a single movement of the actuating-rod a will operate all the several elements of the combination, substantially as shown and described.

10. In a switch mechanism, the combination, with a single actuating-rod, a , and its co-operating parts, of the movable rails and a pair of signaling devices, with compensating locking device between said operating parts and rails, and another compensating device between said operating parts and said signaling devices, the whole combined and arranged in such a manner that when the rails are being moved the signals will remain at rest in a position to indicate "danger," and will not

move to "safety" until after the rails have been moved and locked, the parts being so arranged and connected that a single movement of the actuating-rod a will operate the 5 several elements of the combination, substantially as shown and described.

11. The combination, with the movable rails of a switch, of a compensating locking-movement, $a a' a'' a'''$, a locking mechanism, $b b'$, 10 $d d'$, $F F'$, a detector-bar, E' , and rod E , rod b^2 , connected with a compensating device, KLM , and signaling devices $H I$, the whole so ar-

ranged and combined that a single movement of rod a will unlock the switch, set both signals at "danger," operate the detector-bar, 15 and lock the switch and set one of the signals at "safety."

In testimony that I claim the foregoing as my own I affix my signature in presence of two witnesses.

FRANK H. TREACY.
